UNITED STATES PATENT OFFICE.

JOHN T. BINKLEY, OF CHICAGO, ILLINOIS, ASSIGNOR TO HENRY LIKLEY & COMPANY, OF ROCHESTER, NEW YORK, A CORPORATION OF NEW YORK.

LOCKING MECHANISM.

1,370,942.

Specification of Letters Patent.

Patented Mar. 8, 1921.

Application filed December 10, 1919. Serial No. 343,942.

To all whom it may concern:

Be it known that I, JOHN T. BINKLEY, a citizen of the United States, residing at Chicago, in the county of Cook and State 5 of Illinois, have invented a new and useful Improvement in Locking Mechanism, of which the following is a specification.

This invention relates particularly to locking mechanism for suit-cases and other containers; and the primary object is to provide improved locking mechanism which is adapted to secure the sections of the containers automatically together at a plurality of points.

15 The invention is illustrated, in its preferred embodiment, in the accompanying drawings, in which—

Figure 1 represents an upper edge view of a suit-case equipped with the improved locking mechanism; Fig. 2, a sectional view looking at the inner side of the upper wall of the suit-case, the section being taken as indicated at line 2 of Fig. 3; Fig. 3, an enlarged broken sectional view taken as indicated at line 3 of Fig. 2; Fig. 4, a section taken as indicated at line 4 of Fig. 2, showing the locking mechanism in the locking position; Fig. 5, a similar section showing the locking mechanism in released position; 30 and Fig. 6, a broken sectional view through the lock-case looking toward the inner surface of the outer wall of the lock-case.

In the illustration given, A represents the main section, or body, of a suit-case, or container B, the other section, or lid, of the container; C, a plurality of dowels with which the member B is equipped; C', a plurality of sockets, or keepers, for said dowels, with which the member A is equipped; C², 40 a rock-shaft equipped with a plurality of bolts, or catches, C³, which are adapted to engage notches, or shoulders, with which the inner surfaces of the dowels C are provided; C⁴, a spring-lever adapted to actuate the 45 rock-shaft to retract the bolts C³; C⁵, a plate, or mounting, secured to the inner surface of the upper wall of the section A, and serving as a mounting for the rock-shaft and container parts; and C⁶, a lock-case in which is 50 mounted a plunger-like rotatable key-barrel C⁷, which serves as a push-button adapted to actuate the member C⁴ to effect release of the bolts C³; C⁸, a tumbler, or dog, adapted to releasably lock the member C⁷ in projected position; C⁹, a pawl, or latch, adapted to hold the tumbler C⁸ in retracted position; and C¹⁰ a slidable stud, or button, mounted in a slot in the front wall of the lock-case and adapted to disengage the pawl C⁹ from the tumbler C⁸.
60
In the form of container illustrated, the section A has a top wall 1, which is overlapped by a top wall, or flange, 2, with which the section B is provided, the free edge of the flange 2 being indicated at 2^a. The free 65 edge of the section A is equipped with a beaded, or reinforcement, 1^a.
The dowels C are in the form of clips riveted to the flange 2 of the section B. Thus, each dowel has a flange 3 secured, by 70 rivets, as shown, to the flange 2, and has a body-portion 3^a provided with a reduced finger which extends into the corresponding socket C', the finger being provided in its inner side with a bolt-receiving recess 3^b, 75 affording a locking shoulder for engagement with the corresponding bolt C³.
Each socket C' is in the form of a clip having a flange 4 secured by rivets to the wall 1, as shown, and each clip has a swelled 80 socket-portion 4^a which is open at one end to receive the corresponding dowel.
The rock-shaft C² is supported by small brackets 5 applied to the rear, or lower surface, of the plate C⁵. The rock-shaft is 85 equipped with yokes 6 which are rigidly secured to the rock-shaft and serve as arms for actuating the bolts C³. The yokes are shown as formed of wire, with the web-portions 6^a of the yokes extending through transverse perforations with which the inner ends 90 of the bolts, or catches, C³, are provided. The rock-shaft is equipped with torsion springs 7 which tend to force the bolts C³ to the locking position. The outer ends of 95 the bolts C³ are beveled, as indicated at 8, these bevels being adapted to engage bevels 9 with which the extremities of the dowels C are provided, so that the bolts C³ will be automatically retracted and then projected 100 into the recesses 3^b when the sections of the containers are close together.
The plate C⁵ is secured to the wall 1 by rivets 10. The rock-shaft actuating member C² is shown in the form of a steel strip, 105 or spring-lever, which has one end secured by a bolt, or rivet, 11, to the plate C⁵, and which has the other end equipped with a yoke 11^a which engages the web-portion 6^a of the intermediate arm 6 of the rock-shaft. 110 At an intermediate point, the member C² is equipped with an integral loop 11^b which is

adapted to receive the thrust of the push-button C⁷ in the manner illustrated in Fig. 5.

The lock-case C⁶ has an outer plate 12, an inner plate 12^a, and a flange 12^b which extends outwardly from the rear plate 12^a and engages the front plate 12. The plates are secured together by rivets 12^c.

The wall 1 is provided with a rectangular opening, as indicated at 13, which affords 10 a space which receives the body of the lock-case. The front plate 12 of the lock-case is larger than the opening referred to, thus affording a flange which overlaps the outer surface of the wall 1 and is secured to said 15 wall and the plate C⁵ by rivets 14.

The suit-case, or container, is shown equipped with a handle 15 (shown brokenly in Fig. 1), which is secured to the wall 1 and the plate C⁵ by means of rivets 15^a.

20 The key-barrel C⁷, which constitutes also a push-button, is so mounted in the lock-case that it can be rotated by means of a key to effect release from the tumblers, and can move inwardly and outwardly, like a plunger. The key-barrel has an enlarged outer end-portion 16 and a reduced inner end-portion 16^a. At the junction of these two portions is a flange 16^b which engages the outer wall of the lock-case when the 25 member is in projected position. The push-button C⁷ works through suitable perforations in the plates of the lock-case, the plate C⁵, and the lever C⁴, the inner end of the reduced portion 16^a being adapted to bear 30 against the loop 11^b of the lever C⁴, so that the push-button is capable of forcing the lever C⁴ inwardly, in the manner indicated in Fig. 5, and the lever will return the push-button to the projected position when the 35 pressure of the finger is relieved. When the push-button is in the projected position, it normally is engaged by the dog, or tumbler, C⁸, which engages the inner wall, or shoulder, afforded by the flange 16^b of the push-button. A key 17 may be employed to 40 rotate the member C⁷ and force the tumbler C⁸ to the position shown in Fig. 6, where it will be automatically engaged by the latch-pawl C⁹. This leaves the member C⁷ to be 45 free to be operated as a push-button to effect release of the bolts C³ from engagement with the dowels C. When the pressure of the finger is released, the member C⁷ is projected outwardly, and the operator then 50 shifts the slide-button C¹⁰ to effect release of the latch C⁹, thus permitting the tumbler C⁸ to lock the key-barrel C⁷. As indicated, the button C¹⁰ is slidable in a slot 18 with 55 which the front plate 12 of the lock-case is 60 provided.

In the illustration given, there are shown three pairs of dowels and sockets, the central socket being mounted on the outer plate 12 of the lock-case. It will be understood, 65 however, that any desired number of dowels

and sockets may be employed. This will depend, for example, upon the length of the suit-case and upon the degree of security desired.

The manner of operating the improved 70 locking mechanism may be stated briefly. Fig. 4 shows the parts in locked position. In this position, the tumbler C⁸ engages the inner or under wall afforded by the flange 16^b of the key-barrel, thus locking the key-barrel against actuation as a push-button. In this condition, the bolts, or catches, C³, engage the recesses 3^b of the dowels C, so that sections of the suit-case are securely locked together at a plurality of points. 80 When it is desired to open the suit-case, the key 17 is inserted and rotated, thus effecting release of the key-barrel C⁷. The key is then removed and the key-barrel is actuated as a push-button, thereby forcing the lever 85 C⁴ inwardly in the manner illustrated in Fig. 5 and withdrawing the bolts C³ from engagement with the dowels C. After the sections are separated, the pressure upon the member C⁷ is relieved, thus permitting the 90 bolts C³ and the key-barrel C⁷ to return to the projected position. The slide-button C¹⁰ is then removed to effect release of the tumbler C⁸, thereby locking the key-barrel in the projected position. When the lid of the 95 suit-case is closed again, the bolts C³ engage the recesses 3^b of the dowels by snap action. It will be understood that the lever C⁴ is free to move inwardly, while the key-barrel remains locked, during the operation of 100 closing the lid of the suit-case, the bolts C³ being automatically retracted, and then projected into the recesses 3^b during this operation.

The foregoing detailed description has 105 been given for clearness of understanding only and no unnecessary limitation should be understood therefrom, but the appended claims should be construed as broadly as permissible, in view of the prior art.

110 What I regard as new, and desire to secure by Letters Patent, is:

1. The combination with container-sections having walls adapted to close together, of a dowel carried by one of said walls, a 115 socket carried by the other wall for receiving said dowel, a bolt working through said second-mentioned wall and engaging a shoulder at the inner side of said dowel, and a key-controlled push-button working through said second-named wall and having operative connection with said bolt at the inner side of said second-mentioned wall.

2. The combination with container-sections having walls adapted to close together, 125 of a dowel carried by one of said walls and adapted to project over the other wall, said dowel being provided at its inner side with a shoulder, a bolt working through the second-mentioned wall and engaging said 130

shoulder, a spring adapted to project said bolt, and key-controlled means extending through said second-mentioned wall and having operative connection with said bolt 5 at the inner side of said second-mentioned wall.

3. The combination with container-sections having walls adapted to close together, of a plurality of dowels carried by one of 10 said walls, a plurality of sockets carried by the other wall for receiving said dowels, a plurality of bolts working through said second-mentioned wall and adapted to lock the dowels and sockets together, a push-button 15 working through said second-mentioned wall, means mounted on the interior surface of said second-mentioned wall whereby said bolts may be actuated through the medium of said push-button and a spring associated 20 with said last-mentioned means for projecting said bolts.

4. The combination with container-sections having walls adapted to close together, of a plurality of dowels rigidly carried by 25 one of said walls, a plurality of sockets rigidly carried by the other wall for receiving said dowels, a plurality of bolts working through said second-mentioned wall and adapted to lock the dowels and sockets together, a push-button working through said second-mentioned wall, spring-actuated 30 means connected with the inner ends of and serving to project said bolts, and means mounted on the inner surface of said second-mentioned wall whereby said bolts may be retracted through the medium of said 35 push button.

5. The combination of container-sections having walls adapted to close together, of a 40 plurality of dowels carried by one of said walls and provided at their inner sides with recesses, a plurality of sockets carried by the other wall, a spring-actuated rock-shaft mounted on the inner side of said second-mentioned wall and equipped with arms 45 connected with the inner end of said bolts, a lock-case carried by said second-mentioned

wall, a key-controlled plunger mounted in said lock-case, and a member adapted to be actuated by said key-controlled plunger 50 and serving to actuate said rock-shaft to effect retraction of said bolts.

6. The combination with container-sections having walls adapted to close together, of a plurality of dowels carried by one of 55 said walls, a plurality of sockets carried by the other wall for receiving said dowels, a plurality of bolts adapted to lock said dowels and sockets together, a spring-actuated rock-shaft adapted to project said bolts, a lever 60 adapted to turn said rock-shaft to retract said bolts, and a push-button adapted to actuate said lever.

7. The combination with container-sections having walls adapted to close together, 65 of a plurality of dowels carried by one of said walls, a plurality of sockets carried by the other wall for receiving said dowels, a plurality of bolts adapted to lock said dowels and sockets together, a spring-actuated 70 rock-shaft adapted to project said bolts, a lever adapted to turn said rock-shaft to retract said bolt, a push-button adapted to actuate said lever, and key-controlled means adapted to lock said push-button in projected 75 position.

8. The combination with container-sections having walls adapted to close together, of a plurality of dowels carried by one of 80 said walls, a plurality of sockets carried by the other wall for receiving said dowels, a mounting-plate carried by the second-mentioned wall, a plurality of bolts working through said second-mentioned wall and said plate and engaging said dowels, a rock-shaft 85 mounted on said plate and equipped with means for projecting and retracting said bolts, a lever adapted to turn said rock-shaft in one direction, a spring device adapted to turn the rock-shaft in the opposite direction, 90 and a push-button adapted to actuate said lever to effect the retraction of said bolts.

JOHN T. BINKLEY.
